United States Patent

Des. 235,845
Patented July 15, 1975

235,845

MITER BOX ATTACHMENT

Emilio Golisano, 5211 Cool Road, Holiday, Fla. 33589

Filed July 9, 1973, Ser. No. 377,629

Term of patent 14 years

Int. Cl. D8—05

U.S. Cl. D8—71

FIG. 1 is a top perspective view of the miter box attachment of my invention;

FIG. 2 is a front elevation thereof;

FIG. 3 is a top elevation thereof;

FIG. 4 is a bottom elevation thereof;

FIG. 5 is an end view as seen from the right of FIG. 2;

FIG. 6 is an end view as seen from the left of FIG. 2;

and

FIG. 7 is a rear elevation thereof.

I claim:

The ornamental design for a miter box attachment, substantially as shown.
